UNITED STATES PATENT OFFICE.

JOHN CAPUTI, OF HARTFORD, CONNECTICUT.

MUSIC-STAND.

987,547.

Specification of Letters Patent. Patented Mar. 21, 1911.

Application filed October 10, 1910. Serial No. 586,218.

To all whom it may concern:

Be it known that I, JOHN CAPUTI, a citizen of the United States, residing at Hartford, in the county of Hartford and State 5 of Connecticut, have invented a new and useful Improvement in Music-Stands, of which the following is a specification.

This invention relates to those folding stands which are provided for supporting 10 sheet music in convenient position for orchestral and band musicians while they are playing.

The object of the invention is to provide a simple, cheap, and light device of this 15 class which can be readily folded into a very small space so that it can be carried in a musician's pocket, and which can be quickly extended and adjusted to the height desired for use.

20 Figure 1 of the accompanying drawings shows a front elevation of a music stand which embodies the invention with the rack open for use and the standard partially extended. Fig. 2 shows a view of one side of 25 the device when folded for transportation. Fig. 3 shows a view of another side of the folded device. Fig. 4 shows a view on a larger scale of the upper end of the top standard section. Fig. 5 shows an enlarged 30 section of the standard on the plane indicated by the dotted line 5—5 on Fig. 1. Fig. 6 shows a section of the standard on the plane indicated by the dotted line 6—6. Fig. 7 shows a section practically on the 35 plane indicated by the dotted line 7—7 on Fig. 6. Fig. 8 shows a section of one of the legs on the plane indicated by the line 8—8 on Fig. 1.

The device is, when opened, supported on 40 three legs, each of which is formed of a strap section 1 and a section 2, the edges of which are folded around and movable lengthwise along the section 1. The upper end of each section 1 of a leg is pivoted in mortises in a 45 bracket 3. The leg sections are extended with relation to each other to provide a wide base, and they are slid together in order that they may occupy a small space when folded. A thumb screw 4 is arranged to 50 be screwed through the bottom of the bracket for the purpose of preventing the legs from collapsing when they are extended and are supporting the stand.

The bracket 3 may be formed of a part of 55 or may be attached to the lowest section 5 of the standard. The edges of the lowest

standard section are beveled and fitted into an undercut channel in the lower intermediate section 6 of the standard. On the other face of this intermediate section 6 is a dove-tailed tenon 7 which fits into a corresponding channel in one face of the upper intermediate section 8 of the standard. The top section 9 of the standard has its edges beveled and fitted into a dove-tail channel in 60 the back face of the section 8. These sections are capable of being drawn out with relation to each other in order to raise the supporting rack the desired height, and of being telescoped so they may be packed 65 into a short space.

The rack has a central back strip 10 which is provided on its back side with a perforated lug 11. The upper end of the top section of the standard has a hub 12 provided 75 with a pintle 13. This pintle is designed to be slipped into the perforation in the socket 11 on the back of the central strip 10 for the purpose of attaching the rack to the standard. The bottom bar of the rack is 80 formed in two sections 14. These sections are provided with lugs 15 that are connected by pivots 16 with the strip 10. Along the back of each of the bottom bars is a flange 17, and the end of each bar is turned up to form a 85 lip 18.

Hinged on the pivots 16 are the diagonal strips 19. Jointed links 20 connect the bottom bars 14 with the inclined strips 19, and jointed links 21 connect these strips with the 90 central strip 10. All of these parts are desirably formed of light, thin sheet metal, either brass or steel, and are polished or plated as desired. Pivoted to the bottom bars near the outer ends are leaf holding 95 fingers 22 which are desirably formed of small wire. A perforated lug 23 is attached to an arm 24 that projects forwardly from the lower end of the central back strip of the rack.

In order to prepare the device for transportation, the rack is removed from the upper end of the standard and the leaf holding fingers are turned down against the sections of the bottom bar. The connecting 105 links are then doubled in, allowing the inclined strips and the bottom sections of the rack to be folded up together in front of the center strip, and form a short three-sided box. The sections of the standard are telescoped—the top section 9 sliding in the upper intermediate section 8, these two sec-

- tions sliding down on the lower intermediate section 6, and then these sections sliding down on the bottom section 5. The legs are telescoped—the sections 2 sliding up on the sections 1. The screw 4 is loosened, and the legs turned up against the collapsed standard sections. The standard and legs thus folded are connected with the folded rack by inserting the pindle 13 at 5 the upper end of the top standard section 9 into the perforation in the hub 23 at the end of the arm 24 that projects forwardly from the central strip 10 of the rack. The parts are then turned on the pindle as a 10 pivot, and the legs folded into the open side of the box formed by the folded rack. The screw 4 may then be turned up so as to clamp the parts at the end opposite the hinge. 15
- 20 This music stand is very convenient, for it can be quickly folded into a compact space and readily unfolded and extended to any desired height. All of the parts are desirably formed of thin sheet metal, which 25 provides a light and cheap structure, and the construction is such that, although light metal is employed, the device is stiff and supports the sheets of music in a desirable manner.
- 30 The invention claimed is:
A music stand having a telescopic stand-

ard formed of a bottom section with beveled edges, a lower intermediate section having its edges extending forward around the edges of the bottom section and provided 35 with a dove-tail tenon on its rear side, an upper intermediate section having its edges extending forward about the edges of said tenon on the lower intermediate section and extending rearward about the edges of 40 the top section, and the top section with beveled edges fitting in said rear channel in the upper intermediate section, a bracket at the lower end of the bottom section of the standard, telescopic legs hinged to said 45 bracket, and a rack hinged to the upper end of the top section of the standard, said rack having a central back strip, leaf supporting bars and diagonal strips, said bars and strips being pivoted to said back strip, and 50 links connecting said bars and strips near their outer ends, said rack being so hinged to the top standard section that when the rack is folded and the standard is telescoped these parts may be turned together on the 55 hinge and the standard folded between the leaf supporting bars of the rack.

JOHN CAPUTI.
